Parker Cook

Attorney

UNITED STATES PATENT OFFICE.

WILLIAM E. WINE, OF TOLEDO, OHIO.

CAR-DOOR LOCK.

Application filed January 10, 1922. Serial No. 528,245.

To all whom it may concern:

Be it known that I, WILLIAM E. WINE, a citizen of the United States of America, residing at Toledo, in the county of Lucas and State of Ohio, have invented certain new and useful Improvements in Car-Door Locks, of which the following is a specification.

My invention relates to new and useful 10 improvements in car door locking means, and more particularly to locks that are adapted to support and retain the doors of a hopper car in their closed position.

One of the objects of the present invention is to provide a locking device that is exceedingly simple in construction, readily assembled, cheap to manufacture and easily and readily secured to the car doors.

As is well known to those skilled in the 20 art, the hoppers in a car are angularly disposed with relation to the car floor and the doors are swung from a point at the top of the sides of the hopper.

The present invention contemplates a 25 hook secured to the outside of the hopper while the lock comprises a body plate on which is a latch and dog, the plate to be secured to the lower end of the door and at the side thereof. Although only one hook 30 and one lock is shown in the drawings, it will, of course, be understood that a similar hook and latch will be supplied for the other side of the hopper and door so that the door will be retained and locked 35 from its opposite outer corners.

With these and other objects in view, the invention consists in certain new and novel arrangements and combinations of parts as will be hereinafter more fully described and pointed out in the claims.

Referring now to the drawings showing a preferred form of my invention:

Fig. 1 is a fragmentary view of the side of a hopper showing the hook fastened 45 thereon, the lock secured to the hopper door, a fragmentary portion of the door being shown and in its closed position.

Fig. 2 is a sectional view taken on line 2—2 of Fig. 1 looking in the direction of the arrow, and

Fig. 3 is a bottom plan view of the lock secured to the bottom of the door.

Referring now to the several figures, a fragmentary portion 1 of the side plate of a hopper is shown together with an outer 55 flange 2 on a hopper door 3. The hinge point of the door 3 is not shown, but it will be understood that it is at a point near the top of the hopper. Securely riveted to the side of the hopper is a casting 60 4 having its lower end formed in the shape of the hook 5 which extends beyond the outer edge of the hopper plate and beyond the flange 2 of the door 3. This hook 5 has the supporting ledge 6 formed thereon which ledge extends parallel with the outer 65 free edge of the hopper side plate 1.

Securely riveted to the bottom of the door 3 and directly behind the flange 2 is the triangular bracket plate 7 which is provided 70 with the integral bosses or posts 8, 9, and 10 which bosses all extend beyond the opposite sides of the plates and are each drilled as at 11 for the reception of rivets 12.

The portions of the bosses 8, 9 and 10 75 on the side of the plate form legs which rest on the bottom of the door 3 through which the rivets 12 are passed so that the plate 7 will extend in a plane below that of the outer edge of the flange 2. The portion of the bosses 8 and 10 which extend 80 from the opposite side of the plate 7 form bearings for the reception of a pivotal latch 13 and a dog 14, the lower boss 9 at this side of the plate and the upper boss 8 having a strap 15 riveted to them to retain the dog 14 and hold the latch 13 from lateral movement, while the downward movement of the latch 13 will be limited by the boss 9 as may be clearly seen in 85 Fig. 3.

The location of the casting 4 with relation to the plate 7 is such that when the door is closed and the latch 13 is in its locked position as shown in the different figures, it will rest on the ledge 6 of the hook and cannot be lifted or removed from this position until the dog 14 is swung rearwardly, which may be done by striking the outwardly extending lug 16 of the door with 90 a hammer or other instrument.

The casting 4 as well as the plate 7 and latch 13 may be slightly cored or ribbed as 95 shown in the several figures to provide suffi-

cient strength for these members, as these locking devices, as a whole, must be relatively strong as the doors and the load are comparatively heavy ones.

5. The shape of the lower outer edge of the hook 5 is such that it will raise the latch as the door is swung to its closed position so that the latch will drop into place on the ledge when the door is in its final or closed 10 position. In other words, the latch will drop in place on the closing of the door and will there be further securely held in place by the jamming of the dog into position.

From the foregoing it will be seen that the 15 door may be provided with the outwardly extending flange 2 which will strengthen the door and also shelter the bosses or posts on the plate 7 from injury, while at the same time, the flange does not offer any obstruction to the locking device as these bosses are of sufficient length to hold the lock beyond the lower edge of the flange.

It will also be seen that I have provided a lock which is extremely simple, that will 25 drop into place when the door is closed and on the other hand cannot become accidentally disengaged in use.

Although I have shown the locking device 30 in conjunction with a hopper door, it will be understood that the device might well be used with drop bottom doors on cars of other types.

Many slight changes may be made without 35 in any way departing from the spirit and scope of the invention.

What I claim as new and desire to secure by Letters Patent is:

1. A car door locking device comprising 40 a body plate, having posts formed thereon, said posts extending beyond the opposite sides of said plate, and said posts being drilled, a latch pivotally secured to one of said posts, a dog pivotally secured to another of said posts, and the lowermost post 45 forming a lower limit of movement for said latch.

2. A car door locking device comprising a body plate, three posts arranged about and extending transversely on each side of said 50 body plate, the portions of the posts on one side of the plate forming legs, adapted to be secured to a door, a dog pivotally secured to one post on the opposite side of said plate and a latch pivotally secured beneath said dog to another of said posts, the lowermost post on this side of the plate forming a limit for the downward movement of said latch.

3. In combination with a hopper and door 60 having an outwardly extending flange thereon, a hook secured to the side of the hopper, a body plate secured to the bottom of the door, integral legs formed on one side of said plate, and oppositely disposed bosses

on the other side of said plate, said legs 65 and said bosses forming transversely arranged posts, said posts being provided with openings therein, a latch member pivotally mounted on one of said bosses, a dog mounted on the other of said bosses and the lowermost boss forming a stop for the said latch, a strap connected with the lowermost boss and the boss forming a pivotal point for said dog, and said latch co-operating with said hook when the latch is in its lower position to retain the door in its locked and closed position.

4. In combination with a hopper and door, a hook secured to the side of said hopper, a body plate, posts extending 80 through said body plate and the portion of said posts on one side of the plate forming legs to be secured to the door, and the portions of the posts on the opposite side of the plate forming respectively pivotal posts 85 and a stop, a latch secured to one pivotal post and a dog mounted on the other of said pivotal posts, a strap connecting the pivotal post of the dog and the stop to retain the dog and latch member on said posts, said latch member resting on said hook and held against movement when the door is in its closed position and said dog forming an auxiliary locking means for said latch.

5. A car door locking device including 90 in combination with a swinging door having an out-turned flange formed along one of its edges, a plate secured to the outer face of the door near the said flanged edge thereof, a locking bar pivoted upon the 95 plate, the same overlying the said flange and extending beyond the edge of the door, a stationary hook secured to the car side and arranged for cooperation with the said locking bar and a dog pivotally associated with the said locking bar and arranged to retain the same in engagement with the said hook.

6. The combination with a hopper, of a door hinged thereto and adapted to close the opening thereof, a pair of fixed hooks 100 adapted to be secured to the opposite sides of said hopper adjacent the side edges of said door, a pair of pivoted latches carried by said door and each adapted to cooperate with one of the said fixed hooks, a dog 105 pivotally connected to said door adjacent each of said latches, said dogs being adapted to maintain said latches in engagement with said hooks, said hooks, latches and dogs co-operating to prevent sliding movement of 110 said door with respect to the hinge pintles thereof.

7. The combination with a hopper, of a door pivoted thereto and adapted to close the opening thereof, a pair of fixed hooks 115 connected to the side walls of said hopper, portions of the said hooks being adapted to lie adjacent the side edges of said door,

brackets connected to said door, said brackets each having pivotally connected thereto a latch member cooperating with the said adjacent hook, and a dog adapted to overlie said latch, said dogs when in locked position preventing disengagement between said latches and hooks, the said hooks cooperating

with the side edges of said door to prevent sidewise movement thereof, and said hooks, latches and dogs cooperating to prevent 10 bodily endwise movement of said door.

In testimony whereof I affix my signature.

WILLIAM E. WINE.
